J. H. OBERMAN, JR

PUMP CYLINDER

Original Filed Dec. 11, 1922

UNITED STATES PATENT OFFICE.

JOSEPH H. OBERMAN, JR., OF GRANVILLE, IOWA.

PUMP CYLINDER.

Original application filed December 11, 1922, Serial No. 606,108. Divided and this application filed August 29, 1923. Serial No. 659,960.

To all whom it may concern:

Be it known that I, JOSEPH H. OBERMAN, Jr., a citizen of the United States, residing at Granville, in the county of Sioux and 5 State of Iowa, have invented certain new and useful Improvements in Pump Cylinders, of which the following is a specification.

This application is a division of an application filed by me December 11, 1922, Serial No. 606,108.

The present invention relates to the working cylinder of a pump and seeks to provide a durable lining therefor.

15 The invention is illustrated in the accompanying drawing and will be hereinafter fully set forth.

In the drawing:

Figure 1 is a side elevation of a portion of 20 my pump;

Fig. 2 is a vertical section, and

Fig. 3 is a detail perspective of the upper end of the lining.

In the drawing, 3 denotes a portion of a 25 base having a guiding and supporting sleeve 6 thereon, and 9 denotes a standard supporting the pump-operating mechanism. A head 31 and a fulcrum post 45 are carried at the upper end of the standard 9 and

30 the lever 46 is fulcrumed upon the post to extend through the head and be connected to the bar 42 which is guided by the head and coupled to the upper end of the plunger rod 48. The plunger rod 48 ex-

35 tends downwardly through the upper cylinder 50 and into the lower cylinder 51. It is to be understood that the lower cylinder 51 may be disposed at any depth, to be determined by the depth of the well, and in

40 the present illustration it is shown as threaded into a flange 52 on the under side of a bridge piece 13 which is provided with passages whereby the water may be delivered at the well or directed to a more dis-

45 tant point, as desired. If, however, the well is very deep, the cylinder will be connected with this flange by an intermediate pipe or tubing, the length of which will, of course, be determined by the depth of the

50 well, the lower end of the lower cylinder being equipped with a suction pipe or otherwise arranged to admit the water. The plunger rod 48 is preferably constructed in sections connected by a coupling sleeve

55 so that the parts may be readily as-

sembled and disassembled as occasion may require, and upon the upper end of the lower section is carried the upper plunger 56. The upper cylinder 50 has its upper end threaded into the lower end of a cylindrical block or head 62 which has a reduced upper end 63 provided with flat faces, as shown at 64. A nipple 501 is threaded into the upper end of the block 62 and upon the upper end of the nipple is secured a cap 65 60 which encircles the plunger rod 48 and serves as a guide for the same. The coupling block or head 62 fits closely but rotatably within the sleeve 6, and this sleeve is constructed with a helical slot or opening 66 in which a pin or stud upon the head 62 may play, a roller 68 being preferably mounted upon the said stud to reduce the frictional wear. The helical slot or opening 66 in the sleeve 6 extends nearly 70 75 around the complete circumference of the sleeve, and at its upper end it opens into a longitudinally disposed notch 69 which will permit vertical movement of the stud 67 and the roller 68 so that, when the parts 80 are properly positioned, the plunger rod, the coupling head, nipple, and cylinder may be lifted vertically and drawn through and from the sleeve 6.

The lower end of the upper cylinder 50 85 is disposed within a packing cup 75 secured upon the upper side of the bridge piece 13, a suitable gasket 76 being interposed between the upper surface of the bridge piece and the under surface of the packing cup, as will be readily understood. The packing cup is provided internally with an annular shoulder 77 against which the edge of the packing ring or diaphragm 78 may engage, the said packing ring or diaphragm 90 resting upon the upper end of a spider 79 which is threaded onto the lower end of shoulder or collar 80 which is threaded onto the cylinder with the packing ring disposed between the spider and the shoulder and 95 clamped thereby. It will be readily understood that, when the parts are associated in proper relation, the packing will be forced against the internal surface of the packing cup and the pressure of the water 100 which may reach the packing ring will simply force it outwardly more closely against the packing cup and thereby aid in making the joint leak-proof. The plunger 105 56 works closely within a lining 81 in the 110

- cylinder 50, which lining is of brass, porcelain, or other material that will not corrode under the action of the water. The lower end of the lining is flared, as indicated at 5 82, so that the plunger may readily enter the same in the event that it should happen to make a stroke carrying it below the lining, while the upper end of the lining is constructed with claws or spurs 83 fitting 10 in openings 84 in the cylinder. The said claws or teeth 83 prevent downward movement of the lining, while the flared formation on its lower end will prevent upward movement thereof. The slots 84 in the cylinder provide drain openings so that if, 15 through wear, the washers or packing on the upper plunger should leak the water cannot rise into the head 62 and freeze there to hold the plunger rod.
- 20 The shoulder 80 is provided externally with longitudinal grooves or notches 85 so that it may be readily engaged by a turning tool when the parts are to be separated. If repairs to the plunger or the cylinder 25 should be necessary, the flat bar 42 which constitutes the upper extremity of the plunger rod is disconnected and removed from the head. One of the head-securing bolts is then removed and the head 31 may 30 then be swung rearwardly about the other bolt as a pivot. The elements fastening the head 62 in the sleeve 6 are then withdrawn and a wrench or other tool is fitted to the reduced end 63 of the coupling head 62 35 and said head is rotated so that the stud thereon will be brought to the lower end of the vertical notch 69, after which the cap 65 and the nipple 501 are firmly grasped and lifted. It will be readily noted 40 that the diameter of the head 62 and the

internal diameter of the sleeve 6 are somewhat greater than the external diameter of the packing 78 so that, when the cylinder is lifted, it may be drawn through the sleeve 6 until the lower end of the plunger 45 rod is above the upper end of the said sleeve, whereupon the plunger may be supported by resting upon the upper edge of the sleeve 6. The plunger rod is then disconnected from the said coupling and the 50 plunger and the cylinder may be repaired at once or laid aside to be repaired as circumstances require or permit. Inasmuch as the coupling head 62 is firmly secured to the cylinder 50, the rotation of the head will, 55 of course, rotate the cylinder and, therefore, the parts mounted on the lower end of the cylinder will rise with it as the roller 68 travels upwardly along the helical slot 66. The plunger rod may possibly tend to move 60 downwardly through the cylinder as this upward movement is imparted to the cylinder, but such downward movement of the plunger will be arrested by contact of the yoke at the upper end of the plunger rod 65 with the cap 65 so that the plunger will be withdrawn from the well with the cylinder.

Having thus described the invention, what is claimed as new is:

In a pump, the combination of a cylinder 70 having openings through its wall, of a lining having its upper end provided with laterally projecting teeth to engage said openings and having its lower end flared beneath the lower end of the cylinder, a plunger 75 working in the said lining, and means for operating the plunger.

In testimony whereof I affix my signature.

JOSEPH H. OBERMAN, JR. [I. S.]
